REFRIGERATION

Edward Rice, Jr., New York, N. Y.

Application July 7, 1933, Serial No. 679,435

6 Claims. (Cl. 62—91.5)

This invention relates to improvements in refrigerating methods and apparatus for use with solid refrigerants, such as solid carbon dioxide, water ice, brine ice, etc.

5 An object of the invention is to provide a means for transferring heat to a solid refrigerant at a higher rate than provided in previously known methods, the refrigerant being used in the usual and ordinary processes of refrigerated storage 10 and transportation of perishable foodstuffs.

Another object is to provide a means for transferring heat to small quantities of a solid refrigerant at the same rate as to comparatively large quantities, the refrigerant being used in the usual 15 and ordinary processes of refrigerated storage and transportation of perishable foodstuffs with the result that approximately constant refrigerating temperatures can be maintained substantially as long as any of the refrigerant remains.

20 Another object is to provide a means for transferring heat to small quantities of a solid refrigerant at the same rate as to comparatively large quantities, the refrigerant being used for cooling a fluid such as air or water, thus making it possible to use smaller quantities of the refrigerant than heretofore for a desired rate of heat transfer and to maintain the same rate of heat transfer 25 substantially as long as any of the refrigerant remains.

30 Another object is to provide a means for maintaining substantially constant temperatures in the refrigeration of perishable foodstuffs within a range of approximately 0° F. to 50° F. when using solid refrigerants, such as solid CO₂ or 35 brine ice of a considerably lower temperature than that required in the refrigerating process.

More specifically an object is to provide a solid 40 metallic heat conductor between the area or mass to be refrigerated and the solid refrigerant with sufficient surface in a uniform or controlled heat exchange relation with the refrigerant, with sufficient surface in heat exchange relation with the refrigerated area or mass, and with sufficient heat transfer capacity or cross section to pick 45 up and transfer to the refrigerant the maximum amount of heat as required to effect the desired refrigeration.

More specifically an object is to provide a solid 50 metallic heat conductor of the above characteristics for use with low temperature solid refrigerants, such as solid CO₂ and brine ice, in combination with means for controlling and regulating—(A) The heat transfer to the conductor from the refrigerated area (B) The heat transfer from the conductor to the refrigerant (C)

The heat transfer along the conductor—or a combination of these means—for the purpose of regulating the temperature of the refrigerated area.

Another specific object is to provide a solid 60 metallic heat conductor of the above characteristics which is commercially practicable in refrigerated storage and transportation of perishable foodstuffs, and which can be constructed of cheap available metals such as aluminum or 65 copper; which can be easily made of bent or welded plates or cast or extruded forms of such metals; and which provides the necessary heat-absorbing and heat-emitting surfaces and heat transfer capacities without interfering with the 70 usual and ordinary practices in construction of refrigerated storage and transportation units using solid refrigerants, such as household refrigerators, ice cream cabinets, motor truck bodies, railroad cars and containers, etc. 75

Figures 1 to 4, inclusive, and 1a are diagrammatic vertical sectional views of a refrigerated compartment incorporating various embodiments of my invention, and

Figs. 5 to 14, inclusive, are respectively diagrammatic fragmentary sectional views illustrating other modifications within the scope of my invention.

During the past two summers I have designed and had constructed and commercially used a 85 variety of improved forms of refrigerating apparatus for the storage and transportation of perishable foods, ice cream etc. which employ as the source of refrigeration solid refrigerants such as solid carbon dioxide, water ice, or brine 90 ice in combination with an extended solid metallic heat conductor which is chilled either by direct contact with the solid refrigerant or by some other uniform or controlled heat exchange relationship with the refrigerant. 95

The characteristics of this metallic heat conductor must be such that (a) it forms a principal path of heat transfer between the refrigerated area or mass and the solid refrigerant—(b) it has a surface area in suitable heat exchange 100 relationship with the space or mass refrigerated, this surface area being sufficiently extended to provide the number of square feet of heat absorbing surface required to absorb the heat removed from the refrigerated area, at 105 the temperature differential ranges used in any given apparatus between the conductor surface and the refrigerated area—(c) that it has a minimum cross sectional mass at any particular point sufficient to conduct in the direction of 110

the solid refrigerant the heat absorbed by the surface extended beyond that point, at the temperature differential ranges used in any given apparatus between the heat absorbing conductor surfaces and the conductor surfaces exposed to the solid refrigerant—(d) it has a surface area in suitable heat exchange relationship with the solid refrigerant, this surface always being smaller than the surface exposed to and absorbing heat from the refrigerated area.

This general method of using solid refrigerants is fully disclosed and claimed in my pending application Serial #467,999, filed July 14, 1930, and various forms of apparatus for carrying out the method are there described. In this application I wish to disclose more specifically the principles of this method of refrigeration, to describe in more detail the characteristics of the solid metallic heat conductor which is the essence and concrete embodiment of the invention, and to claim improved forms of the conductor and ways of using it.

The use of this metallic conductor conforms to the usual and well known principles of heat absorption and emission by, and transfer through, a solid homogeneous material. For instance a certain number of heat units per hour are to be absorbed to maintain the required temperature in a household refrigerator, say equal to the melting of one pound of water ice per hour. In using water ice for this purpose which melts at 32° F. a metallic conductor of copper or aluminum can be chilled to an average temperature say of 36° to 44° F. by direct contact with a surface of the ice. This conductor can in turn chill the air of the refrigerator to say an average of 47° F. in an 80° room. To accomplish this approximately 144 B. t. u.'s per hour must be transferred from the air of the refrigerator to the ice, or sufficient to melt one pound of ice per hour. Where air circulates by natural convection over a cooling surface under these conditions approximately 1½ B. t. u.'s per hour per ° F. differential between the air and the cooling surface, per square foot of cooling surface can be absorbed. Therefore about fifteen square feet of chilled conductor surface is exposed to the air at an average temperature of 40° F., thus absorbing approximately 15 sq. ft. x 1½ B. t. u.'s per hour x 7° F. differential—157 B. t. u.'s per hour—this meets condition (b) above. Next a surface area of the conductor must be in direct contact (in the present instance) with the ice. This surface need be only a fraction of the surface absorbing heat from the air; and in this fact lies the great practical advantage in this method of refrigeration, as well as one of the principal objects of the invention, as it permits satisfactory refrigeration with small amounts of solid refrigerant. There is no exact physical data covering this heat transfer from the metal to a solid refrigerant but experimental observation shows that it is from fifty to several hundred times as much per unit area per degree difference in temperature as from the air to the conductor surface. For instance with a sufficiently thick conductor, say $\frac{3}{8}$ " of aluminum, fifteen square inches of water ice contact with the conductor can absorb the heat that is picked up from the air by fifteen square feet of conductor surface exposed to convection currents in the form of fins—this corresponds to condition (d) above.

With a given surface exposed to the air and a certain amount of ice available for minimum con-

tact with the conductor then condition (c) above becomes an absolutely essential consideration in constructing a conductor for use in this method of refrigeration. After means are provided to get the heat into the metal conductor, by providing a necessary area of chilled surface, and to get the heat out of the conductor to the solid refrigerant, by providing an area of the conductor in uniform or controlled heat exchange relationship with the refrigerant, it is necessary to make the conductor sufficiently thick to transfer the maximum amount of heat to be taken out of any given refrigerated space or mass to effect the desired refrigeration under the most adverse conditions of actual use. This thickness is determined for the minimum temperature differential that it is feasible to use between the points where the heat enters and leaves the conductor, or between any two points along the conductor path. The rate per hour for this form of heat transfer is established for all the available metals and can be easily ascertained in the usual physics handbooks. Briefly for any given metal it varies directly as the cross section and temperature differential used. For instance, other features being equal, approximately twice as much heat will be transferred per hour by an aluminum plate $\frac{1}{4}$ " thick as by one $\frac{1}{8}$ " thick for the same temperature differential; or approximately the same amount of heat will be transferred per hour by conductor plates, other factors being equal, made of $\frac{1}{8}$ " copper, $\frac{1}{4}$ " alum num, or $\frac{3}{4}$ " iron. It is to be expected that these rules can not be very reliable for overall temperature differentials of less than 2° or 3° F. or more than 20° to 30°; or for excessively long distances, say over 6 or 8 feet; or for excessively thin or thick conductors, say a conductive capacity of less than $\frac{1}{8}$ " of aluminum or over $\frac{1}{2}$ " of copper. But the conductor can always be constructed with enough surface and sufficiently thick to take care of extreme conditions of use, and once constructed its heat transfer properties do not change. And experimental observation and wide commercial use show that—for the commonly available solid refrigerants such as water ice, brine ice and solid CO₂; and for the cheaply available metals such as aluminum and copper, and to a lesser extent iron; and for ordinary commercial purposes in which it is common to use solid refrigerants, such as the transportation and storage of perishable foodstuffs—it is possible to construct refrigerating apparatus on the principles described above that is a great improvement over anything previously known in the art for use—with solid refrigerants.

In effect such apparatus provides a new means of transferring energy or power in the form of heat, and greatly enlarges the entire field of use for solid refrigerants as a class, as well as providing a means of temperature control in the use of solid CO₂, often called "dry ice", the newly developed solid refrigerant which is now coming into such wide commercial use.

Heretofore the transfer of heat to solid refrigerants has been either—

From the air or other fluid or mass to be cooled directly to the surface of the ice. Here the inexorable laws of physics, governing heat transfer from the fluid or mass to the ice on a square foot basis, and the steady reduction of volume and surface of a solid refrigerant when heat is applied, have made it inevitable that an excessive amount of the refrigerant had to be provided to supply sufficient surface to take up the required amounts

of heat; and that there has been a steady rise in refrigerating temperatures due to the reduction in the heat absorbing surfaces of the refrigerant.

Or the heat transfer to the refrigerant has been through the walls of a refrigerant container or support in contact with the refrigerant, the heat reaching the ice at the area of contact—which in some cases provided a constant surface of the refrigerant itself direct for heat absorption, but which resulted in such small surfaces being available for that purpose that either very limited refrigeration was secured or such large containers had to be used as to be commercially impracticable. When necessary to segregate the ice metal containers were often used, usually of galvanized iron, but the function of the metal was altogether as a convenient material for constructing the containers and segregating the ice to control meltage, etc. and not as disclosed above to form an extended thick walled metal conductor of heat to the ice. The metal of the containers on which the ice rested acted to slow up heat transfer from the air to the refrigerant, not to facilitate it, and no heat in any useful amount was absorbed by the metal beyond the actual point of contact with the ice. The thinner the metal was in contact with the ice the more rapid the heat transfer; whereas in the extended metal conductor method described above the thicker the metal the more rapid the transfer.

In constructing refrigerating apparatus for solid refrigerants using this solid metallic heat conductor it is not necessary that all the heat taken from the refrigerated space or mass be passed through the conductor, but only as stated in condition (a) above that it provide "a principal path of heat transfer"; although in usual practice most of the heat is thus transferred. It is sufficient that the fixed heat absorbing surface and transfer capacity provided by the conductor be large enough to take up the minimum amount of heat necessary to maintain a useful temperature when the volume of the refrigerant is considerably reduced—say to 5% or 10% of the bunker capacity. There will always be some heat get into the bunker space, and to the ice surface exposed there, through the walls of the bunker no matter how well insulated.

The previous method of building ice cream delivery truck bodies for use with solid carbon dioxide—as compared with similar truck bodies now built with a solid metallic heat conductor constructed on the principles described above forms an excellent illustration of the old case of transferring heat directly to the surface of the ice by air circulation or directly through the wall of a metallic ice container at the area where it is in contact with the refrigerant—as compared with the new way disclosed in the present invention. Formerly the insulated ice cream truck compartment included a "dry ice" bunker in the top back corner made of light galvanized iron with an access hatch through the roof and a galvanized double wall inner lining of the compartment built integrally with the galvanized bunker forming a 1 inch hollow space completely surrounding the storage compartment, in which CO₂ gas and air from the bunker circulated. There was no direct air and gas access or circulation between the bunker and the storage space. Heat coming in through the walls of the compartment or through the door was absorbed either through the inner lining wall by the cold CO₂ gas or air, which was thus caused to circulate by natural convection over the ice in the bunker, or it was

absorbed by the contacting surface of the ice through the part of the bunker wall on which the ice rested. Although the compartment used only 30 or 40 lbs. of ice per day at the most yet the bunker usually had a capacity over 100 or 150 lbs. in an effort to get enough ice surface for circulating currents to contact to insure refrigeration as the ice melted, and the surface decreased, and to secure increased heat absorbing ice contact area with the bottom of the bunker. In a storage compartment about 3½ ft. x 5 ft. x 2½ ft. high this bunker provided, when first loaded with 100 lbs. of dry ice, approximately 7 sq. ft. of ice surface exposed to the gas and air circulation and 2 sq. ft. in direct contact with the bottom of the bunker.

In operation the transfer of heat by the closed gas and air circulation to the ice surface was very inefficient; and the heat transfer across the bottom of the bunker to the contacting ice was confined to such a small intensely cold area exposed to the storage compartment that there was considerable frosting. This, combined with a steadily diminishing ice surface, say a total of 2½ sq. ft. at 20 lbs. of ice, resulted in a slowly rising temperature, as well as unsatisfactory temperatures even when first iced. Although widely used as the best type available at the time these trucks never provided a means of using solid CO₂ efficiently or to its full possibilities as a refrigerant.

In comparison trucks recently put on the market with a solid metallic heat conductor, or heat transfer agent, between the dry ice and the storage compartment constructed as shown in this application have proved entirely satisfactory for holding ice cream and other frozen foods in the hottest weather. Using the same insulation and general storage compartment construction as before the method and means of transferring heat to the ice is radically different. The entire top inner wall of the compartment is made of a copper or aluminum plate sufficiently thick to maintain the required chilled surfaces. For a compartment of the size mentioned above copper ½ inch thick or aluminum ¼ inch thick forming the top wall will provide enough conductive capacity and exposed surface to put the closed compartment to minus 40 degrees F. if required, or easily maintained zero under the hardest operating conditions of heat, door openings, etc. down to the last 2 or 3 lbs. of ice. This compares with a low of from 0 degrees to 15 degrees F. for the older types of trucks with approximately 20 degrees F. on hot days—too high for ice cream or proper holding of any frozen foods. In the new "conductor" type the dry ice rests in a small insulated space on top of the conductor plate, either directly on the plate to give maximum refrigeration for a given size and capacity of conductor, or in a controlled-spaced-distance from the plate whereby the heat transfer to the ice is slowed up and controlled for the purpose of regulating the temperatures in the refrigerating compartment to meet various working conditions. The bunker space usually provides for two half cakes of ice 10 in. x 10 in. x 5 in. high, but one piece 10 in. x 10 in. will present sufficient heat transfer surface to the conductor. The conductor presents to the refrigeration compartment approximately 17½ sq. ft. of surface which is constant, irrespective of the volume of ice, and which will keep approximately constant temperature to the last pound or two of ice. In this type of construction practically all the heat which gets to the ice, with the exception of that coming di-

rectly through the top of the ice bunker hatch, arrives through the medium of the solid metallic heat conductor to one surface of the ice. The heat coming in through the roof, outside that 5 through the bunker hatch, is absorbed by the conductor plate and taken to the ice before it can reach the storage compartment. The heat coming through the side walls, floor, door and by means of goods stored in the compartment, is 10 transferred by convection and radiation to the conductor plate forming the inner ceiling and enters along through the plate to the ice. For more severe conditions or for use with brine ice at -6° F. the conductor plate can be thickened and 15 bent down to form part of the vertical side walls as well as the top. The "conductor" can take an infinite variety of forms, thicknesses, etc., the one described immediately above being a convenient and successful application to ice cream 20 truck construction.

Besides being able to transfer heat to small amounts of solid refrigerants at a rate before unequalled in similar refrigerating apparatus, one of the principal advantages of this "conductor" method of using solid refrigerants is that 25 it makes possible a controlled use of solid refrigerants such as solid CO₂ which sublimes at a temperature far below those required for ordinary refrigeration purposes, or such as a brine 30 ice that can be made so as to melt from minus 6 degrees to about minus 30 degrees F. As explained above the number of sq. ft. of heat absorbing conductor surface and the difference in 35 temperature of this surface below that of the refrigerated space determines the amount of heat absorbed per hour—and thus the effective refrigerating temperatures. Obviously with a very cold refrigerant, like solid CO₂ at minus 110 degrees F., a small conductor surface could be 40 chilled to a very low temperature and theoretically produce the same results as a much larger surface at a higher temperature. But in practice a difference in temperature of more than 8 or 10 degrees F. between the conductor surface 45 and the air temperature of the refrigerated space does not result in a comparative increase in heat transfer from the air; and in most cases there is sufficient moisture in the air to cause considerable frosting of the low temperature surface 50 which steadily cuts down heat transfer. Therefore it is preferable to use as far as possible a large surface high temperature conductor with a low temperature refrigerant like solid CO₂.

This large surface chilled a few degrees below 55 the ordinarily required refrigerating temperatures, which range between 0 degrees and 50 degrees F., can only be secured when using solid CO₂ as the refrigerant by means of some intermediate heat transfer agent such as a circulating gas or liquid, or such as a suitably formed good 60 heat conducting metal. As mentioned above heat transfer to the refrigerant by a gas, including air, is not always satisfactory, and can not be maintained at a sufficiently high rate to the 65 comparatively small surfaces of the refrigerant to meet most refrigerating means. Heat transfer by a circulating liquid such as alcohol or in freezing brine can transfer a considerable amount of heat to a small surface of the solid CO₂ especially when forced circulation is used, but as a principal means of heat transfer for refrigeration purposes such a system is not the subject of this application. A combination of circulating gas and liquid in the form of a condensable refrigerant such as methyl chloride, etc.

can also be used as a heat transfer means, but that also is not the subject of this application. The only remaining convenient means for providing the required heat transfer agent is the use of a solid good heat conducting metal which 80 can provide the necessary heat absorbing surface and transfer capacity, which can provide the necessary function of transferring heat at a comparatively high rate to a small surface of the refrigerant, and which permits of using 85 means to control the rate of heat flow from the refrigerated area to the refrigerant via the conductor in order to regulate the temperature of the refrigerated area. Various forms of such a solid metallic heat conductor for use with solid 90 refrigerants such as solid CO₂ are included in the subject matter of this application, and various means, in combination with the conductor, for controlling the heat flow from the refrigerated area to the solid refrigerant via the conductor 95 are included in the claims.

These various means, as indicated above, include:

(A) Ways for controlling the heat transfer from the refrigerated area to the conductor. 100 When the refrigerated area consists of an enclosed space in which a fluid circulates by convection, such as air, water or a non-freezing liquid, and the conductor is of such a form that a wall can be set up to form a confined space 105 in which the fluid can flow past the conductor, then a convenient way of control is to establish manually or thermostatically operated valves in this confined passage which restrict, or at times shut off entirely, the flow over the conductor as 110 may be desired, thus limiting the amount of heat that has access to the conductor and so regulating the temperature of the refrigerated area. When it is impossible to set up this confined convection passage because of the nature of the refrigerated area, or when the character of the conductor permits, it is sometimes convenient to 115 control the heat transfer to the conductor by placing predetermined amounts of insulation on the exposed surface of the conductor where it is 120 extended away from contact with the refrigerant and does not form an integral part of the refrigerant containing bunker space.

(B) Ways for controlling the heat transfer from the conductor to the refrigerant. This 125 forms probably the best method of controlling the temperature of the desirable large heat-absorbing conductor surface chilled only a few degrees below the refrigerated area, when using low temperature solid refrigerants like solid carbon 130 dioxide. This method operates by controlling the spaced relation of the conductor and the solid refrigerant. When the ice is hard down on the bare conductor, a maximum heat flow results, and consequently the lowest refrigerating temperatures 135 for a given apparatus. If the ice is held more than $\frac{3}{4}$ " from the conductor, there is not much effective heat transfer. However, from the point of contact to about $\frac{1}{2}$ " away from the conductor provides a region where the surface 140 of the solid CO₂ can be held in a controlled heat exchange relationship with the conductor by which the temperature of the chilled conductor, and, therefore, the refrigerating temperatures, can be varied at will. The first break in the direct contact of the ice with the conductor will 145 result in a marked resistance to the heat flow; and every change of a fraction of an inch toward or away from the conductor will speed up or retard the heat flow correspondingly. This action 150

is in accordance with the ordinary physical laws of heat flow already referred to. Heat is accumulated by the conductor and brought by it to that part of its surface opposing the ice surface. 5 The amount of this heat taken up by the ice varies directly as the temperature differential between the surface of the ice and the conductor surface opposed to it; this differential in turn being largely determined by the distance between 10 the ice and conductor and the substance filling this space. These last two factors are easily varied during the operation of a given refrigerating apparatus, and, therefore, provide a most efficient means for regulating the refrigerating temperatures. 15 The first factor, or temperature differential, changes as a result of the variation of the other two factors and so need only be regarded as a corollary indication of what has taken place.

Thus it is the nature and amount of the substance between the ice and the conductor that governs in this method of temperature control. The rate of heat transfer varies with the substance. Also the rate will vary with the thickness or distance between the ice and the conductor—the further apart the less heat transmitted, and vice versa. The substance can be of any convenient character, preferably a solid, or a fluid like air or CO_2 gas, or a non-freezing liquid, or a combination of substances, depending 30 on the means used for varying the amount of the substances. The substance may be:

(1) A solid in unit form such as sheets of paper, compressed board like cardboard or $\frac{1}{8}$ th" thick pieces of pressed wood, or sheets of metal. 35 These may be put into place to the required thickness when putting the ice into the bunker and changed by lifting out and replacing the ice.

or (2) A sufficiently rigid piece of material may be used to support the ice and this material 40 in turn raised and lowered in relation to the conductor by any convenient mechanical elevating means operated by hand, or by automatic power applied by the action of a thermostat located in the refrigerated space. In this form the maximum heat flow can occur when the movable support means is in its lowest position, and a diminishing heat flow results as the ice is raised. In 45 operation this form can function by alternately lowering the ice hard down to take up the heat at a higher rate than required and then raising the ice far enough away to take less heat than required, the action being controlled by a thermostat and resulting in the average heat flow required. Here the substance forming the resistance to the heat flow is a solid or a fluid (CO_2 gas and air) or a varying combination of the two. 50 Or as is more usual, this form can function by having the supporting means, under thermostatic control from the refrigerated space, take a stable position, holding the ice in approximately uniform heat-exchange relation with the conductor changing slightly from time to time to meet changing conditions in the refrigerated 55 space, etc. Or this stable position may be achieved without thermostatic control by hand-operated mechanical elevating means. The spaced support for the ice can also take the form of a hollow chamber between the ice and the conductor which is filled, or partially filled, with a non-freezing liquid, such as alcohol, the level of the liquid being regulated by a thermostatically controlled feed. When it is full of liquid, maximum heat transfer results. When the liquid is

lowered, the gas filled space above the liquid gives added resistance to the heat flow.

or (3) Relatively small ice supporting areas can be set up on the conductor where it is opposed to the ice surface, well insulated against heat flow from the conductor, and sufficient heat applied to these areas under thermostatic control from the refrigerated space, to permit the ice to melt more rapidly at these points and the whole ice

80

mass to be lowered nearer the conductor, thus increasing the rate of heat flow as necessary to keep the conductor chilled to the required temperature. Any conveniently controlled source of heat may be used for this purpose including electrically heated resistance wires fixed to the

85

supporting insulated areas; or a fluid, such as air or alcohol circulating in a closed pipe system which picks up heat from the refrigerated space, or outside it, and discharges this heat to the ice through that part of the system on which the ice

90

is supported, namely the insulated small areas, having a thermostatic valve located in the system; or heat may be taken up from the solid metallic conductor or from the air of the refrigerated space by a miniature solid metallic conductor

95

system and transferred as required to the support areas in any of the ways used in the principal heat transfer for refrigerating purposes; or heat may be supplied as required to the insulating supporting areas from the controlled inter-

100

action of suitable chemicals. This way of regulating the heat-resisting space between the ice and the conductor uses principally a gas and air-filled space and a balanced condition such as is

105

described above, although it may also operate by the alternate hard on and off action also described above. This method is based on a fact

110

I have discovered that solid CO_2 when supported on small insulated areas over a metallic conductor which is a source of heat will not melt down over the supporting areas and approach the conductor so long as the supports are colder than the conductor surface opposed to the ice.

115

(C) Ways of controlling the heat transfer through the conductor itself. These include vari-

120

ous means for breaking the continuity of the heat-conduction along the metallic conductor by actually breaking the conductor at some convenient point beyond its point of contact with the refrigerant in order to form a controlled resistance to the heat flow similar to the resistance between the ice and the conductor described above in para-

125

graph B. The break must be so located and sufficiently great as to cut down the heat flow below the minimum required for refrigeration purposes and the controlling means for closing this break

130

must be adequate to increase the heat flow to the maximum requirements. For instance a break of one-half inch or one inch may be provided and the break mechanically adjusted or closed by hand

135

or thermostatically controlled means, or a suitable separate heat-conducting means automatically moved into place as required. One way of regulating the heat flow across the break, or re-

140

sistance interposed in the conductor itself, is to provide a short length of flexible metallic heat conductor which is moved in and out of contact with the conductor, preferably being fastened permanently to one side of the break and moved by thermostatically controlled means in and out

145

of contact with the other side, or maintained in a balanced heat-exchange position with the conductor on the other side of the break. Such a flexible metallic conductor section can be formed from a flexible flat copper cable made up of small

150

woven copper wires and which is thick enough to possess in effect the heat transfer capacity of the conductor itself and still have considerable flexibility of movement. This form is desirable as there is of necessity considerable resistance to heat flow across any break in the conductor and the mending of the break should be over as large an area as possible to cut down this resistance sufficiently. In using copper and aluminum for the conductor in solid sheet or casting form, and also using the same form for connecting the break, it is very hard to make this contact accurately and consistently over a sufficient area because of the tendency of the metals to warp, but if the flexible section as described is interposed, a larger area of close contact can be maintained more consistently because the flexible part can be pressed up hard against the rigid part of the conductor to overcome the surface irregularities and other causes of resistance to heat flow. This is an invaluable feature because the first small break in the contact of the two metallic faces sets up a large resistance to the heat flow, just as the first break between the solid refrigerant and the metal conductor also does.

These three broad ways, which I have described under A, B and C above, of controlling the refrigerating temperature when using solid CO_2 as a refrigerant in combination with the solid metallic conductor are all involved in the general principle of setting up a "conductor resistance" in the path of heat flow formed by the conductor—a principle which is disclosed in my pending application Serial No. 467,999, filed July 14, 1930. A more detailed description is included in this application and various improved means which I have developed for carrying out the principle are now claimed.

The more complete disclosure in this application both of the principles of the solid metallic conductor and of the "conductor resistance" is made for the purpose of providing a basis for the wider use of the invention. There are illustrated herewith, and claims are made for, a few of the particular forms and improvements which are embodied in actual refrigerating apparatus used at the present time. But I do not wish to limit myself to these specific designs as almost every commercial use of a solid refrigerant for the refrigerated storage or transportation of perishable foodstuffs, or other refrigerating purposes, calls for a different design and a different way of applying the principles of the invention. There are always different refrigerating temperatures to be considered, different rates of heat transfer, different forms of storage spaces and different forms of solid refrigerants and bunker capacities—and the conductor must be constructed accordingly.

The attached drawings illustrate various preferred forms of the solid metallic conductor used with various solid refrigerants, also various preferred means for controlling the rate of heat transfer from the refrigerated space to the refrigerant via the conductor, all of which embody advances made since the filing of my application Serial No. 467,999, filed July 14, 1930.

Figures 1 to 4, inclusive, and 1a show designs particularly adapted for use of dry ice or brine ice in large storage compartments or in truck bodies and railway containers. In Fig. 1, the conventional insulated casing is indicated by the reference numeral 1, this casing embracing the storage compartment 2. 3 is a metallic conductor formed preferably of a single sheet of copper

or aluminum, which in the present instance forms the effective upper wall surface of the refrigerated compartment. For use with dry ice, this conductor may be of $\frac{1}{4}$ " aluminum or $\frac{1}{8}$ " copper. As illustrated, the conductor 3 also forms the bottom wall of the refrigerant compartment 4, and 4a indicates a mass of the solid refrigerant supported on the conductor. The refrigerant can rest directly on the conductor, as shown in Fig. 1, or it can be held in a controlled spaced relation with the conductor by any suitable form of conductor resistance, such for example as indicated at 5 in Fig. 4. The conductor resistance 5 interposed between the refrigerant and the conductor regulates the temperature of the extended heat-absorbing surfaces of the conductor, and hence the temperature of the refrigerated space. While it is preferred to form the conductor of a single continuous sheet, the conductor may be fabricated by welding or otherwise securing relatively small sections together. If so fabricated, however, it is most important that the thickness or cross section is never decreased as the point of heat transfer with the refrigerant is approached, as this would form a bottle neck through which the passage of heat would be restricted. Also it is preferable not to make any joints in the conductor except by welding, since if for example two parts of a copper conductor were soldered together, there would be a large drop of temperature across the joint because solder is a much poorer heat conductor than copper.

In this form of refrigerated container almost 100% of the heat abstracted from the refrigerated space reaches the lower surfaces of the refrigerant through the conductor; also the heat coming through the hottest wall of the compartment, namely, the roof, is absorbed by the conductor without reaching the inside of the refrigerated compartment. Sometimes for convenience of construction, the conductor plate may be dropped down a few inches from the ceiling. This construction is illustrated in Figure 1a wherein the corresponding parts are designated by the same reference numerals used in Figure 1 and in the subsequent Figures 2, 3, and 4.

Fig. 2 shows the same general construction as illustrated in Fig. 1 modified to adapt it more particularly for use with brine ice. In this case the conductor plate is turned down the sides of the insulated compartment to afford a more extended heat-absorbing surface and the conductor preferably should be thickened to the extent of about 50% on account of the higher temperature of the refrigerant. Since the construction in the embodiments of my invention illustrated in Fig. 2 and also in Figs. 3 and 4 is essentially the same as that illustrated in Fig. 1, the corresponding parts are designated by the same reference numerals.

In the embodiment illustrated in Fig. 3, I have provided the conductor 3 with a hinged flap 3a permitting insertion of the refrigerant in the compartment 4 from the inside of the refrigerated compartment 2.

Fig. 4 illustrates a compartment adapted when required for carrying refrigerated temperatures above freezing. In this instance, an insulated horizontal baffle 21 is spaced a few inches below the conductor plate 3 with circulating air access openings at 23. A body of insulation 22 is secured directly to the conductor plate under the ice compartment. The insulated baffles 21 have turned-up edges 21a to carry off condensation

which may drip down from the conductor plate when the higher refrigerating temperatures are used. In operation, when the storage compartment and its contents are cooled down to a steady state, the circulating air goes up at the ends and down the center, as indicated by the arrows. However, during the cooling-down operation, the circulation as shown is reversed. This apparatus will operate at frozen temperatures with dry ice 10 directly on the conductor, or at above freezing using dry ice with a conductor resistance 5 as shown, or with brine ice in direct contact with the conductor.

Figs. 5 to 14, inclusive, illustrate various forms 15 of conductor resistance used for regulating the rate of heat transfer from the refrigerated space to dry ice via the extended metallic conductor.

In Fig. 5, the spaced relation, or thickness of conductor resistance, between the conductor 3 20 and ice 4 is regulated by means of a lever 37 which is pivoted at the point 38. The ice is supported on the metal plate 35 preferably of the same material as the conductor 3 previously described, and this plate is raised or lowered by 25 means of the lever 37 which may be operated in any convenient manner. The conductor resistance is formed by the plate 35 in combination with the gas-filled space 36. It will be noted that in Figs. 5 to 14, inclusive, I have used the same 30 reference numerals to indicate directly corresponding functional elements.

In Fig. 6 a support for the ice is formed by the hollow tube 39 which is insulated at 40 from the conductor 3. Tube 39 is filled with a non-freezing fluid, such as alcohol, and forms a closed 35 circulating system. Incorporated in the down leg of this system is valve 41 operated by a conventional thermostatic bellows 42, which in turn is responsive to the temperature of the refrigerated space through bulb 43. In operation when the refrigerating temperatures are higher than desired the valve 41 remains open, the liquid circulates in the direction of the arrows, the portion of the tube supporting the ice becomes warmer 40 melting that portion of the ice resting on the tube and allowing the remaining portions of the bottom surface of the ice to approach the conductor 3. This action results in an increased chilling 45 of the conductor, a lowering consequently of the refrigerating temperatures and ultimately a closing of the valve 41 when these temperatures go below the thermostat setting. The ice resting on the tube then ceases to melt so rapidly because the tube is insulated from the warmer conductor 50 and the ice begins to melt back from the conductor proper. The spaced relation, or conductor resistance, between the ice and conductor is thus increased, the refrigerating temperatures gradually go up and the cycle is repeated. Any convenient means under thermostatic control may be 55 used to heat the insulated ice support, the one described being only one of several preferred forms.

Figs. 7 to 11 inclusive show various ways of introducing the controlled conductor resistance in the path of the metallic conductor itself, as distinguished from its location between the ice and the conductor. In Fig. 7 the continuity of the metal conductor is broken by the gap 3''. This 60 gap is closed by the plate 3' hinged on one side to the conductor 44. The plate is caused to swing in and out of contact with the conductor surfaces on either side of the gap by means of the conventional thermostatic bellows 42, which in turn is responsive to the temperature of the refrigerated

space through bulb 43. In operation when the temperature goes up the bellows expands, pushing the plate 3' into contact with both sides of the conductor, and an increased flow of heat takes place from the extended portions of the conductor via the conductor to the ice. When the temperature gets too low the bellows contracts and pulls the plate out of contact. The heat flow is reduced, the temperatures go up and the cycle is repeated. The apparatus illustrated in Figs. 8 65 to 11 goes through exactly the same operation. In Fig. 8 the gap is closed by a loosely packed springy material 3' such as copper ribbons or shavings. When compressed by the bellows 42 an increased heat transfer takes place because of the greater density and hence conductivity of the material. When the pressure is released the particles spring apart and the heat transfer lessens. A large coiled spring 46 can be imbedded in the 70 particles to assist in separating them. In Fig. 9 a variation of the make and break plate of Fig. 7 is shown. A pair of plates 3' hinged at 44 are forced in and out of contact with the conductor 3 by action of the bellows 42 working through the member 45 which slides in contact with plates 100 3'. A spring 46 helps maintain this contact. In Fig. 10 the break is closed by a section of flexible conductor preferably made of woven copper wire. It is secured firmly to the fixed conductor on one side of the break, and is moved into contact on the other side of the bellows. In Fig. 11 the same flexible conductor section is used in slightly different form and location. The bellows action is applied by lever 47 which is pivoted at 48.

Figs. 12 and 13 show the use of a liquid confined in the conductive path, the level of which controls the heat transfer rate. The liquid level in turn is controlled by the usual thermostatically operated bellows. In Fig. 12 a conductor resistance 5 is 115 provided between the ice and the conductor in the form of a hollow metal pad filled with alcohol. The pad is connected with a bellows 51 the two forming a closed fluid system containing a fixed amount of alcohol just enough to completely fill 120 the pad when the bellows is contracted. A second bellows 42 operates under thermostatic control from the refrigerated space as previously described to contract and expand bellows 51 containing the alcohol. When the temperature of the 125 refrigerated space goes up bellows 42 expands, bellows 51 contracts and pad 5 is filled with liquid permitting a maximum heat transfer. As the temperature drops bellows 42 contracts, bellows 51 expands and the liquid 49 in the pad drops 130 leaving an air filled space in the pad over the liquid which is a much poorer conductor of heat to the ice than the liquid. When the temperature again rises the air space is pressed out and the cycle is repeated. A very small hole in the top 135 of the pad permits the air to get in and out. Fig. 13 shows an apparatus operating in the same way as Fig. 12, except that the fluid compartment is located in a definite break in the conductor as shown outside the ice compartment.

Fig. 14 shows a definite break in the conductor path where the heat transfer across the break is principally by radiation between two relatively large opposing surfaces of the conductor. In this apparatus the heat transfer across the break is 145 regulated by means of a series of thin polished bright metal plates 52 arranged on pivots 53 to swing like the leaves of a shutter from a horizontal to a vertical position. When they are in a horizontal position the maximum heat transfer 150

will take place between the opposing faces of the conductor and the refrigerating temperatures will be lowest. When in a vertical position the amount of radiated heat transfer will be cut down 5 by reflection from the bright surfaces and the temperatures will be higher in the refrigerated space. The action of the shutters can be controlled by any convenient known mechanical means, operated by hand or thermostatically 10 under control from the refrigerated space.

I claim:

1. In refrigerating apparatus, cooled by a solid refrigerant such as water ice, brine ice, or solid carbon dioxide, a solid metallic heat conductor 15 presenting surfaces for heat absorption from the refrigerated space or material of greater area than the surfaces of the conductor presented in the refrigerant-containing space for heat transfer to the refrigerant; the capacity of said conductor to 20 transmit heat along in the direction of the refrigerant from the said surfaces presented for heat absorption being sufficient, by reason of its thickness or cross section, to maintain the said heat-absorbing surface areas at a lower temperature 25 than that of the refrigerated space or material; said heat-absorbing surface areas being formed by a substantially horizontal thick metal plate located at the top of the refrigerated space, and the solid refrigerant being supported by a portion 30 only of said solid metallic conductor.

2. In refrigerating apparatus, cooled by a solid refrigerant such as water ice, brine ice, or solid carbon dioxide, a solid metallic heat conductor presenting surfaces for heat absorption from the 35 refrigerated space or material of greater area than the surfaces of the conductor presented in the refrigerant-containing space for heat transfer to the refrigerant; the capacity of said conductor to transmit heat along in the direction of 40 the refrigerant from the said surfaces presented for heat absorption being sufficient, by reason of its thickness or cross section, to maintain the said heat-absorbing surface areas at a lower temperature than that of the refrigerated space or 45 material; said heat-absorbing surface areas being formed by a substantially horizontal thick metal plate located at the top of the refrigerated space, and the solid refrigerant being supported by a portion only of said solid metallic conductor, together with means for access to the refrigerant-containing space through a wall of the refrigerated space, or from within the refrigerated space 50 through the said conductor plate.

3. In refrigerating apparatus, cooled by a solid refrigerant such as water ice, brine ice, or solid carbon dioxide, a solid metallic heat conductor presenting surfaces for heat absorption from the refrigerated space or material of greater area than the surfaces of the conductor presented in 60 the refrigerant-containing space for heat transfer to the refrigerant; the capacity of said conductor to transmit heat along in the direction of the refrigerant from the said surfaces presented for heat absorption being sufficient, by reason of 65 its thickness or cross section, to maintain the said heat-absorbing surface areas at a lower temperature than that of the refrigerated space or material; said heat-absorbing surface areas being formed by a substantially horizontal thick metal

plate located at the top of the refrigerated space, and the solid refrigerant being supported by a portion only of said solid metallic conductor, together with a wall vertically spaced below the said heat-absorbing surface areas of the conductor plate to form an open-ended duct through which air from the refrigerated space may circulate in contact with the said heat-absorbing surface areas.

4. In refrigerating apparatus, cooled by a solid refrigerant such as water ice, brine ice, or solid carbon dioxide, a solid metallic heat conductor presenting surfaces for heat absorption from the refrigerated space or material of greater area than the surfaces of the conductor presented in the refrigerant-containing space for heat transfer to the refrigerant; the capacity of said conductor to transmit heat along in the direction of the refrigerant from the said surfaces presented for heat absorption being sufficient, by reason of its thickness or cross section, to maintain the said heat-absorbing surface areas at a lower temperature than that of the refrigerated space or material; said heat-absorbing surface areas being formed by a substantially horizontal thick metal plate located at the top of the refrigerated space, and the solid refrigerant being supported by a portion only of said solid metallic conductor, together with means for controlling and regulating the transfer of heat from the refrigerated space or material to the solid refrigerant, said means being located between the metallic conductor and the solid refrigerant.

5. In refrigerating apparatus, cooled by a solid refrigerant such as water ice, brine ice, or solid carbon dioxide, a solid metallic heat conductor presenting surfaces for heat absorption from the refrigerated space or material of greater area than the surfaces of the conductor presented in the refrigerant-containing space for heat transfer to the refrigerant; the capacity of said conductor to transmit heat along in the direction of the refrigerant from the said surfaces presented for heat absorption being sufficient, by reason of its thickness or cross section, to maintain the said heat-absorbing surface areas at a lower temperature than that of the refrigerated space or material; said heat absorbing surface areas being formed by a substantially horizontal thick metal plate located at the top of the refrigerated space, and the solid refrigerant being supported by a portion only of said solid metallic conductor, together with means for controlling and regulating the transfer of heat along the metallic conductor in the direction of the refrigerant from the said heat-absorbing surface areas, said means being formed by a break in the metallic continuity of the conductor, and means for varying the heat flow across said break.

6. In refrigerating apparatus cooled by a solid refrigerant, a space adapted to contain the material to be refrigerated, a solid metallic conductor located at the top of said space, and a refrigerant containing bunker located above a portion only of said conductor, the said conductor being formed by a substantially horizontal plate which forms the principal path of heat transfer between said space and the solid refrigerant.

EDWARD RICE, JR.
